FOLDING COMB

George C. Hampson, Fred C. Keller, and
Donald E. Nichols, Fresno, Calif.

Application September 29, 1950, Serial No. 187,448

7 Claims. (Cl. 132—15)

1

The present invention relates to combs and more particularly to folding combs having a folded compact condition for stowing and carrying purposes.

It is well known that pocket combs are objectionable in that if of adequate size for convenient employment they are so bulky as to be inconvenient to carry. The teeth tend to snag on other articles carried therewith and to subject pockets in which they are carried to excessive wear by contact of the comb teeth therewith. It is also well known that the teeth are frequently damaged by other articles with which the combs are carried and rapidly become soiled unless protectively housed.

The difficulties encountered in the carrying and stowing of pocket combs are also characteristic of the carrying of combs in ladies' hand bags and the like.

An object of the present invention is to provide a folding comb which is collapsible into a compact condition so as to occupy a minimum of space and in which condition the teeth are shielded against damage thereto and soiling thereof as well as for the purpose of obviating snagging of materials therewith and the subjection of a pocket, purse or the like in which the comb is carried to excessive wear and/or perforation by the teeth.

Another object is to provide a folding comb that is conveniently and easily manipulated between a compact condition and an operable condition with teeth extended therefrom.

Another object is to provide a comb having foldable teeth and means for locking the teeth rigidly in operable position.

Another object is to provide improved elements and arrangements thereof in a device of the character and for the purposes set forth that is economical to manufacture, durable in structure, and fully effective in its operation.

Further objects and advantages will become apparent in the subsequent description in the specification.

In the drawing:

Fig. 1 is a side elevation of a folding comb embodying the principles of the present invention illustrated in compact condition as for stowing or carrying.

Fig. 2 is a side elevation of the comb shown in Fig. 1 adjusted for operation with comb teeth extended in substantial parallelism.

Fig. 3 is a fragmentary longitudinal section of the comb showing the teeth and other elements thereof in compact condition.

2

Fig. 4 is a fragmentary longitudinal section of the comb showing the teeth and other elements thereof positioned for combing operations.

Fig. 5 is a transverse section of the comb, as taken on line 5—5 of Fig. 2.

Fig. 6 is a fragmentary view of the lower side of the comb in operable condition, as viewed from line 6—6 in Fig. 2.

Referring in greater detail to the drawing:

10 The comb employs an elongated hollow body 10 which conveniently may be cylindrical in form and fabricated from tubular metal, plastic, glass, or other material. As clearly evident in Fig. 5, the body has a slot 11 formed longitudinally, and as evident in Fig. 6, two substantially parallel series of openings 12 aligned longitudinally of the body diametrically opposite to the slot 11. It is to be understood that a single series of openings aligned longitudinally of the body is employed 15 when a single row of teeth is desired. The employment of two parallel series of openings accommodates a pair of rows of teeth, soon to be described, so that the interstices therebetween are of smaller size and a resultant "finer" comb 20 achieved.

An elongated hollow locking slide 15 is slidably fitted to the body 10 and likewise is conveniently formed from tubular metal, plastic, glass or other suitable material. The locking slide is provided 25 with a longitudinal slot 16 in registration with the slot 11 and two substantially parallel series of openings 17 formed therethrough diametrically opposite to the slot 16 in alignment longitudinally thereof. The openings 17 are individually registrable with corresponding openings 12 in the body and thus the number and arrangement thereof is controlled by the number and arrangement of the openings in the body. The slots 11 and 16 define a channel longitudinally of the body 10 between a handle end portion thereof identified by the numeral 18 and an opposite end identified by the numeral 19.

An elongated control member 22 is slidably fitted to the channel provided by the slots 11 and 16 for reciprocal positioning therein longitudinally of the body. The control member has a number of grooves 23 corresponding in number to the series of openings 12 and 17 formed longitudinally in the control member inwardly disposed to the body. The control member provides an elongated transversely arcuate cap 24 integral therewith in covering relation to the slot 11. At the handle end of the control member, a pair of arcuate brackets 25 is laterally extended therefrom exteriorly of the body in slidable peripheral

embracing engagement therewith. Similarly, at the opposite end of the control member, a pair of arcuate brackets 26 is laterally extended from the control member exteriorly of the body in slidable peripheral embracing engagement therewith. For convenience in supporting the comb of the present invention, a clip 27 is mounted longitudinally of the body on the cap 24 intermediate the brackets 25.

As clearly evident in Figs. 3, 4, and 5, the control member 22 is located in predetermined spaced relation to the openings 12 and 17 through the body 10 and locking slide 15. A plurality of substantially uniform elongated teeth 30 are pivotally mounted in the control member 22 and individually extended through aligned openings 17 and 12. It will be noted that there is a series of teeth pivotally mounted in each of the grooves 23, each of which series is extended through a corresponding series of aligned openings in the locking slide and body.

The teeth may be pivotally mounted in any desired manner but it has been found convenient to provide a pair of facing indentations 31 in the walls of each groove 23 adjacent to each tooth and mounting the teeth in the grooves by means of oppositely extended studs 32 integral with the teeth nested within the indentations 31. For such mounting, the teeth 30 are formed from any suitable material having adequate resilience to permit sufficient compression of the studs 32 for snap insertion of the teeth upwardly into their respective grooves and expansion of the studs into their respective indentations. The studs 32 exemplify suitable pivotal axes for the teeth 30 transversely disposed to the control member 22 and aligned openings 17.

The teeth are of a length appreciably greater than the spacing of the control member 22 from the openings 12 and 17 so that when the control member is moved to bring the pivotal mounting of its teeth 30 into substantial alignment with said teeth's respective openings 17 and 12, the teeth will be extended from the body sufficiently for combing convenience. In order releasably to constrain the control member in such slidable position with the teeth extended from the body in substantially right angular relation thereto, inwardly convex dimples 33 are formed in the body in positions overlaid by the brackets 25 and 26 when the control member is in said position and complementary dimples 34 formed in the brackets for releasable engagement with the convex dimples 33.

When the control member 22 is slid toward the handle end 18 of the comb by overcoming the resilient nesting of the dimples 33 and 34, the teeth 30 are retracted into the body and the extended end portions 35 located within the openings 12, as shown in Fig. 3. The length of the slot 11 is preferably such that movement of the control member 22 further toward the handle end of the body is precluded by the abutting of the control member against the end of the slot. In order releasably to retain the control member in the position illustrated in Figs. 1 and 3, dimples 36 are formed in the body in positions to nest with the dimples 34 with the control member in retracted position.

As also shown in Fig. 3 the edges of the openings 17 in the locking slide 15 are preferably beveled endwardly of the body 18, as illustrated at 37 in Figs. 3 and 4. Further, the body at the edges of the openings 12 toward the handle end 18 of the body are beveled at 38 to facilitate

reciprocal retraction and extension of the teeth 30.

A boss 40 is rigidly extended from the control member 22 downwardly to a position in abutting relation to the end of the locking slide adjacent to the handle end of the body. As shown in Figs. 3 and 4, the position of the boss 40 is such in relation to the adjacent end of the locking slide 15 that engagement thereof occurs only upon movement of the control member 22 and thus the boss toward the end 19 of the body sufficiently to bring the teeth 30 into substantial right angular relation to the body. The engagement is made just prior to releasable association of the dimples 34 and 33 and the continued movement of the control member and locking slide to bring the dimples into releasable engagement causes the control slide to move in unitary relation with the control member and relatively to the body whereby the teeth 30 extended through the openings 12 and 17 are subjected to shearing forces conducive to dependable clamping of the teeth in operable position.

After the comb is assembled, plugs 50 of desired artistic form are fitted in closing relation to the opposite end portions of the body and secured therein as by sweating, soldering, welding or other means appropriate to the materials employed.

Operation

The operation of the device is believed to be clearly apparent and is briefly summarized at this point.

For stowing and carrying convenience, the control member 22 is drawn toward the handle end 18 of the body 10 and releasably maintained in such position by the nested association of the dimples 34 and 36. This position of the control member frees the locking slide from restraint and draws the teeth 30 upwardly through the openings 12 and 17 into the retracted position shown in Fig. 3. In such retracted and compacted condition the teeth are shielded from damage and soiling and containers such as pockets, purses and the like in which the comb is stowed or carried protected against damage from the teeth.

The comb is conveniently supported, if desired, by means of the clip 27 on the edge of a pocket or in other convenient position much in the well known manner of fountain pens, pencils and the like.

To employ the comb, the control member 22 is thrust toward the end 19 of the body until the dimples 33 and 34 are in releasably nested association. As previously described, the movement of the control member slides the teeth 30 downwardly through the openings 17 and 12 and pivots the teeth to the positions shown in Figs. 2 and 4 in substantially right angular relation to the body 10. With the control member 22 positioned as described, the boss 40 urges the locking slide 15 endwardly in the body 10 and subjects the teeth to a clamping action between the body and locking slide incident to a slight misalignment of the openings 12 and 17. The employment of a plurality of rows or series of teeth slidably positioned in a plurality of series of openings 12 and 17 enables the provision of a comb having closely adjacent teeth in relation to the direction of movement of the comb teeth through hair during normal employment of the comb. As indicated, when a relatively coarse comb is

desired, only a single row or series of teeth and openings are employed.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described our invention, what we claim as new and desire to secure by Letters Patent is:

1. A folding comb comprising an elongated hollow body having a slot formed longitudinally therein and a series of openings formed therethrough in alignment longitudinally of the body diametrically opposite to the slot, an elongated hollow locking slide slidably mounted in the body having a slot formed longitudinally therein in registration with the slot of the body and having a series of openings individually in registration with the openings in the body, an elongated control member slidably mounted in the slots of the body and locking slide for reciprocal movement in the body in a path defined by the slot in the body, a plurality of teeth pivotally mounted on the control member for pivotal movement about axes transversely of the slot in the body and extended individually through the openings in the locking slide and body, the control member being reciprocally positionable in the body between a position with the teeth extended from the body and a position with the teeth retracted into the body, and a boss mounted on the control member engageable with the locking slide when the control member is moved to teeth extending position whereby the locking slide is shifted longitudinally of the body to clamp the teeth in extended position in their respective openings.

2. A folding comb comprising a hollow cylindrical body having a slot formed longitudinally therein and a series of openings formed therethrough in alignment longitudinally of the body diametrically opposite to the slot, a hollow cylindrical locking slide mounted in the body for slide movement longitudinally thereof having a slot longitudinally thereof in registration with the slot in the body and a series of openings individually registerable with corresponding openings in the body, an elongated control member slidably mounted in the slots of the body and locking slide having support brackets laterally extended therefrom exteriorly of the body in sliding embracing relation thereto, a plurality of teeth pivotally mounted on the control member for movement about axes transversely thereof and individually extended through registered openings in the body and locking slide, the control member being reciprocally positionable in the body between a teeth extending position and a teeth retracting position, and a boss mounted on the control member engageable with the locking slide upon movement of the control member to teeth extending position adapted to lock the teeth in positions extended through the openings by urging the locking slide endwardly in the body.

3. A folding comb comprising a hollow cylindrical body having a slot formed longitudinally therein and two parallel series of openings formed through the body in alignment longitudinally thereof diametrically opposite to the slot, a hollow cylindrical locking slide located concentrically in the cylindrical body having a slot

formed longitudinally therein in registration with the slot in the body and having two parallel series of openings formed therethrough individually registerable with corresponding openings in the body, an elongated control member slidably mounted in the slots of the body and the locking slide for reciprocal movement longitudinally thereof having mounting brackets extended laterally therefrom in sliding peripheral embracing relation to the exterior of the body, two parallel series of teeth pivotally mounted in the control member for pivotal movement about substantially parallel axes transversely of the body and individually slidably extended through the aligned openings in the body and locking slide whereby reciprocal movement of the control member extends the teeth in parallelism through the openings and retracts the teeth into the body, and a boss rigidly extended from the control member abuttable with the locking slide when the control member is moved to teeth extending position whereby the locking slide is shifted longitudinally relative to the body locking the teeth by resultant shifting of the openings from alignment.

4. A retractable comb comprising an elongated hollow body having a handle end portion and an opposite end portion having a slot longitudinally therein and a series of openings therethrough in alignment longitudinally of the body diametrically opposite to the slot, a locking slide mounted in the body having a series of openings therethrough in alignment longitudinally of the body positionable for registration of the locking slide openings with corresponding openings in the body, said locking slide being reciprocally movable between a position with the openings therein displaced from their respective openings in the body toward the handle end of the body and a position with said openings displaced toward said opposite end of the body from precise alignment with their respective openings, an elongated control member mounted in the slot of the body for slide reciprocal movement therein between a position in the handle end of the body and a position in said opposite end of the body, a plurality of teeth pivotally mounted in the control member for pivotal movement about axes transversely of the path of reciprocal movement thereof in the body having extended ends individually rested in the openings in the body and the locking slide when the control member is located in the handle end of the body and extended from the openings in substantially right angular relation to the body when the control member is located in said opposite end of the handle, a boss borne by the control member adjacent to the locking slide at the handle end of the body engageable with said locking slide on movement of the control member toward said opposite end of the body to urge the locking slide toward said opposite end, and means adapted releasably to constrain the locking slide selectively in its reciprocal positions in the handle end of the body and said opposite end.

5. In a comb of the character described, a body, a locking slide slidably mounted in the body, the body and the locking slide having a series of aligned openings formed therethrough, a control member slidably mounted in the body in spaced parallel relation to the locking slide for reciprocal movement in a predetermined path in the body, a plurality of teeth pivotally mounted on the control member on axes transversely of the reciprocal path of movement of the con-

trol member in the body and individually extended through openings in the locking slide and the body, the control member being reciprocally positionable between a position with the teeth extended through the openings in the body and the locking slide and a position with the teeth retracted into the openings, and means mounted on the control member engageable with the locking slide when the control member is in teeth extending position to shift the locking slide relative to the body and thus to clamp the teeth in the openings in positions extended therefrom.

6. In a comb of the character described, a body having a series of aligned openings formed therein, a locking slide slidably mounted in overlaying relation to the openings for reciprocal movement longitudinally of the series of openings in the body and having a series of aligned openings formed therein concurrently individually registerable with the openings in the body, a control slide slidably mounted in spaced parallel relation to the locking slide for reciprocal movement longitudinally of the series of openings in the body, a plurality of teeth pivotally mounted in the control slide for movement about pivotal axes transversely disposed to the aligned openings in the body and individually extended through aligned openings in the locking slide and body, the control slide being reciprocally positionable relative to the body between a position with the teeth extended through the openings in the body and a position with the teeth retracted into the openings in the body, means mounted on the control slide engageable with the locking slide upon movement of the control slide to teeth extending position to urge the locking slide longitudinally of the series of aligned openings in the body whereby the teeth are clamped in extended position, and coacting means on the body and control slide for releasably constraining the control slide successively in teeth extended and teeth retracted positions.

7. A folding comb comprising an elongated tubular body having a slot formed longitudinally therein and a series of openings formed therethrough in alignment longitudinally of the body diametrically opposite to the slot, an elongated

tubular locking slide slidably fitted within the body having a slot formed longitudinally therein in registration with the slot of the body and having a series of openings individually in registration with the openings in the body, said locking slide being of a length less than the length of the body and providing spaced ends within the body, an elongated control member slidably mounted in the slots of the body and locking slide for reciprocal longitudinal movement in the body in a path longitudinally thereof defined by the slot in the body, a plurality of teeth pivotally mounted on the control member for pivotal movement about axes transversely of the reciprocal path of movement of the control member and individually extended through the openings in the locking slide and body, the control member being reciprocally positionable at the body between a position with the teeth extended from the body and a position with the teeth retracted into the body, and a boss integral with the control member extended therefrom to a position endwardly aligned with the locking slide engageable with an end of the locking slide when the control member is moved to teeth extending position whereby the locking slide is urged longitudinally of the body to clamp the teeth in extended position in their respective openings.
